UNITED STATES PATENT OFFICE.

CHARLES J. PILLING, OF PHILADELPHIA, PENNSYLVANIA, ASSIGNOR TO
GEORGE P. PILLING AND CHARLES J. PILLING, OF SAME PLACE, (CO-
PARTNERS TRADING AS GEO. P. PILLING & SON.)

DESIGN FOR A BLANK FOR RECTAL SPECULUM-BLADES.

SPECIFICATION forming part of Design No. 34,338, dated April 9, 1901.

Application filed February 9, 1901. Serial No. 46,745. Term of patent 7 years.

To all whom it may concern:

Be it known that I, CHARLES J. PILLING, a citizen of the United States, residing at the city of Philadelphia, State of Pennsylvania, 5 have invented and produced a certain new and original Design for a Blank for a Rectal Speculum-Blade, of which the following is a full, clear, and exact description, reference being had to the accompanying drawings, forming 10 a part of this specification.

In said drawings, Figure 1 is a plan view, and Fig. 2 a side view, of the blank.

My invention consists of the design, in novel external outline planular shape or configuration shown, of the blank from a duplicate of 15 which each of the operating-blades of a speculum is produced. The planular shape or con-

figuration shown comprises a shank with a part in irregular outline and an angular projecting portion at one end thereof, the said 20 projecting portion having a concaved outline along one edge.

I claim—

The design for a blank for a rectal speculum-blade, substantially as shown and 25 described.

In testimony whereof I have hereunto affixed my signature this 18th day of January, A. D. 1901.

CHARLES J. PILLING.
